(57) **CLAIM**

The ornamental design for a child seat, as shown and described.

DESCRIPTION

FIG. 1 is perspective view of the child seat showing my new design;

FIG. 2 is a front view of FIG. 1;

FIG. 3 is a rear view of FIG. 1;

FIG. 4 is a top view of FIG. 1;

FIG. 5 is a bottom view of FIG. 1;

FIG. 6 is a left side view of FIG. 1; and,

FIG. 7 is a right side view of FIG. 1.

The broken line showing of opening in FIGS. 1 and 4 and portions of the bottom view in FIG. 5 is included for the purpose of illustrating environmental structure and forms no part of the claimed design.
